UNITED STATES PATENT OFFICE

115,225

DESIGN FOR AN ASTROLOGICAL AND MYSTIC ROBOT

Joseph P. Wilson, Atlanta, Ga.

Application October 21, 1938, Serial No. 80,589

Term of patent 14 years

To all whom it may concern:

Be it known that I, Joseph P. Wilson, a citizen of the United States and resident of Atlanta, Fulton County, Georgia, whose post-office address is 150 Peachtree Arcade Building, Atlanta, Georgia, have invented a new, original, and ornamental Design for an Astrological and Mystic Robot, of which the following is a specification, reference being had to the accompanying drawing, forming part thereof.

Fig. 1 is a front elevational view of an astrological and mystic robot showing my new design.

Fig. 2 is a perspective view thereof, the mystic figure and the crystals shown in Fig. 1 being omitted.

The characteristic features of the design consist of a mystic figure with a crystal positioned adjacent its either side.

I claim:

The ornamental design for an astrological and mystic robot, substantially as shown.

JOSEPH P. WILSON.
